UNITED STATES PATENT OFFICE

BERT EDSON, OF PAWTUCKET, RHODE ISLAND, ASSIGNOR TO NEW ENGLAND LACE MILLS, INC., OF NEW YORK, N. Y., A CORPORATION OF NEW YORK

DESIGN FOR LACE

Application filed March 6, 1931. Serial No. 38,981. Term of patent 3½ years.

To all whom it may concern:

Be it known that I, BERT EDSON, a citizen of the United States, residing in Pawtucket, Rhode Island, have invented a new, original, and ornamental Design for Lace, of which the following is a specification, reference being had to the accompanying drawing, forming

part thereof, in which the figure is a face view of a piece of lace constituting my new design.

I claim:

The ornamental design for lace, substantially as shown.

BERT EDSON.
